UNITED STATES PATENT OFFICE

2,326,801

HIGH FREQUENCY TUBES AND CIRCUITS

George E. Pray and Sebastian Riccobono,
Washington, D. C.Original application September 22, 1938, Serial
No. 231,215, now Patent No. 2,251,951, dated
August 12, 1941. Divided and this application
January 22, 1941, Serial No. 375,417

11 Claims. (Cl. 250—27)

(Granted under the act of March 3, 1883, as
amended April 30, 1928; 370 O. G. 757)

This invention relates to vacuum tubes for use with ultra high radio frequencies and circuits including such tubes.

Among the several objects of this invention are:

To provide vacuum tubes in which cathode-grid transit time losses are reduced to a minimum;

To provide vacuum tubes having nearly uniform path lengths for electrons in the cathode-grid space;

To eliminate eddy currents in the grid structure;

To provide vacuum tubes with high shunt input impedances;

To provide vacuum tubes with low inter-electrode capacities;

To provide, in vacuum tubes, one or more beams of electrons, controllable by potentials applied to the tube electrodes;

To provide circuits and operating methods for utilizing tubes of the type above-mentioned.

In the drawing:

Figs. 1 and 2 are, respectively, a transverse section and a longitudinal section of a duo-diode tube according to our present invention;

Fig. 3 is a schematic diagram of a circuit utilizing the above-mentioned tube as a detector;

Fig. 4 illustrates the use of our tube as a mixer in connection with a local oscillator;

Fig. 5 is a transverse section of a tube according to our invention having multiple control grids and having a focusing plate to direct all electrons to a single anode;

Fig. 6 utilizes the same form of focusing plate as Fig. 5, but has two separate anodes each with its individual control electrode for use in push-pull operation.

This application is a division of our co-pending application Ser. No. 231,215, filed September 22, 1938, Patent No. 2,251,951, August 12, 1941.

For amplification, detection, or oscillation at frequencies of the order of 100 megacycles per second and upward, the vacuum tube input impedance and the cathode to grid electron transit time are the most important factors limiting the efficiency of the tube or circuit. If the input elements of the tube present a low capacitive reactance, then the resonant input circuit must have a low value of inductance, with consequent sacrifice in the resonant gain of the circuit. If the input elements of the tube also present a low shunt resistance, the resonant impedance of the

circuit is greatly reduced, with further loss in sensitivity and loss of selectivity.

This low shunt resistance is due to transit time effect as is well known in the art. In explanation, we will consider a vacuum tube triode; with an electron emitting cathode or filament, an anode whose potential is positive with respect to the cathode, and a control electrode or grid whose potential is varied sinusoidally from positive to negative with respect to the cathode. The cathode will emit a supply of electrons with nearly zero initial velocity, building up a space charge layer around the cathode. As electrons are drawn from the space charge layer, they are replenished by further cathode emission. Since the anode is maintained positive, the potential gradient in the tube places the space charge layer so close to the cathode that it may be considered as being at the surface of the cathode. Then an electron which receives velocity due to positive grid or anode potentials must traverse the distance from the cathode to the grid before the grid current is affected, and from cathode to anode before the anode current is affected. The grid potential is always low compared to the anode potential, so the velocity imparted to an electron in the cathode-grid space is very small compared to the velocity in the grid-anode space. Thus, the cathode-grid transit time is many times greater than the grid-anode transit time for a normal spacing of the electrodes, and is the important factor to consider.

In the vacuum tubes commercially available for use at frequencies above 100 megacycles, with rated negative grid and positive anode (or screen if using a tetrode or pentode) potentials, the time required for an electron to go from the cathode or filament to the grid is of the order of 10^{-9} seconds. At low frequencies this time is negligible compared to the period of one oscillation, but as the frequency is increased this transit time becomes a larger portion of an oscillation. Thus when the grid is driven positive an increase of electron flow is induced, but no grid current flows until these electrons reach the grid. Then as the grid is driven negative, some of the electrons accelerated during the positive portion of the cycle will still produce current in the grid until the grid bias becomes sufficiently negative to overcome the velocity of these electrons, deflecting them toward the anode or turning them back toward the cathode. Thus the grid and anode currents are shifted in phase from their normal relations to the grid voltage, this phase shift being called the "transit angle."

The component of current in phase with the negative grid voltage has the effect of greatly reducing the input impedance of the tube and consuming power from the input circuit.

The electrode materials used in our novel tubes may be any of those well known in the art as suitable for the various purposes, such as tungsten or nickel alloys for grids or control electrodes; molybdenum or nickel alloys for anodes, suppressors, or focusing electrodes; nickel alloy sleeves coated with oxides of barium, strontium carbonate or thorium for cathodes, and tungsten for heaters. All the electrodes are normally supported and their spacing kept constant by means of mica discs at the ends of the electrodes. As hereinafter used, the term "strip electrode" is to be understood as designating an electrode whereof the length is notably greater than the width and, if transversely curved, does not subtend more than a few degrees.

The embodiment of our invention shown in Figs. 1 and 2 is a duo-diode, intended for operation as a detector or rectifier at very high radio frequencies. Within the glass envelope 29 is disposed the cathode support 30 having electron emissive bodies 31 and 32 on diametrically opposite sides thereof and facing the emissive bodies are the electrodes 33 and 34. The electrodes 33 and 34 are placed very close to the respective emissive bodies, the spacing between an electrode and its coating emissive body being but a few thousandths of an inch. The areas of the surfaces of electrodes 33 and 34 are substantially equal to the areas of the respective coating emissive bodies 31 and 32 and the surfaces of the anodes are substantially uniformly spaced from the surfaces of the emissive bodies, whereby electron paths of uniform length are provided between the emissive bodies and the electrodes. The electrodes 33 and 34 may have widths of $\frac{1}{16}$ of an inch and a length of $\frac{1}{8}$ of an inch which gives a low input capacitance on the order of 0.35 micro-microfarad, giving satisfactory operation at frequencies above 500 megacycles per second.

A detector circuit employing the tube of Figs. 1 and 2 is shown schematically in Fig. 3, wherein the electrodes 33 and 34 are respectively connected to the parallel members 35 and 36 of a resonant frame. This frame comprises the members 35 and 36, which may be short rods of conductive material having low resistance connected at their end remote from the tube by a bar 37, with a conductive tuning slider 38 contacting both bars. The bar 37 is provided to reduce dead end losses and the slider 38 may be moved to resonate the frame, as is well known in this art. A variable capacitance 39 may be connected across the frame to provide additional tuning if desired. The input leads to slider 38 are designated by 40 and 41 and by means thereof the alternating potentials are applied to electrodes 33 and 34. The cathode bodies 31 and 32 are connected through a suitable resistor 42 to the slider 38 and the output leads 43 are connected to the opposite terminals of resistor 42 which may be shunted by a capacitance 44. This circuit acts as a full wave detector or rectifier, the radio frequency signals between electrodes 33 and 34 being substantially 180 degrees out of phase with each other, and the demodulated output appears across the output impedance 42, 44. The resonant frame is found to be more advantageous than the conventional inductance for frequencies above 200 megacycles per second.

Fig. 4 depicts our duo-diode used as the first

detector or mixer in a superheterodyne circuit. The circuit elements are the same as in Fig. 3 except that the output impedance is here a resonant circuit comprising an inductance 45 and a capacitance 46, the output energy being taken off through inductance 47 coupled to inductance 45. The output impedance is resonated to a desired intermediate frequency derived from beating the output of local oscillator 48 with the input radio frequency.

In Fig. 5 the construction is modified by having a single anode 73, a single control grid 74, a single acceleration grid 75 and a single focusing plate 76 that extends around the cathode 50 in spaced relation thereto from adjacent one side of anode 73 to adjacent the other side thereof, thus having at least three quadrants around the cathode enclosed by the focusing plate with the anode 73 between the termini of the plate 76 but outside the space enclosed thereby. While the focusing electrode could be extended to enclose all the electrodes, this is undesirable due to the increase in output capacitance that would result.

Operation at high frequency usually makes it desirable to utilize balanced, or push-pull input circuits, feeding into a balanced tube circuit. In the case of a single sided tube, that is, one having one control electrode and one anode, it is necessary to use two tubes to obtain a balanced circuit. The connection between the separate cathodes entails a length of conductor, which, though short, presents appreciable inductive reactance to the signal grid, allowing a possible large difference of radio frequency potential between the cathodes and producing losses in the circuit. Balanced or push-pull tubes embodying our invention have been constructed with a common cathode and double control and anode structures, to obtain greatest efficiency and least input and output capacitances.

The tube shown in Fig. 6 differs from all the preceding types in that the two strip anodes 77 and 78 are placed near each other on one side of the cathode and utilize the same electron stream. The control electrodes 79 and 80 are respectively disposed between the parallel to anodes 77 and 78 and the cathode 50. In this tube the electron stream flows continuously toward the anodes, but since the control electrodes 79 and 80 have applied to them radio frequency potentials that differ substantially 180 degrees in phase the electrons will be attracted to one anode and kept away from the other during one-half cycle and then attracted to the other and kept away from the one during the next half cycle. It is thus seen that this tube operates as a balanced or push-pull unit while the electron stream continues to flow in the same general direction. If desired, accelerating grids may be used in this type of tube. A single space charge grid or a single screen grid, or both, should work satisfactorily with the double elements of this tube.

Wherever in this specification definite values are stated they are given by way of illustration and not of limitation.

The invention herein described and claimed may be used and manufactured by or for the Government of the United States of America for governmental purposes without the payment of any royalties thereon or therefor.

We claim:

1. An electron discharge device, comprising a cathode support, separate electron emissive bod-

ies on opposite sides thereof, each said body subtending substantially less than 180° of angle, means to cause said bodies to emit electrons, and a separate electrode disposed closely adjacent to each of said bodies, said electrodes each having a surficial area substantially equal to that of the respectively adjacent said body and being substantially equidistant in all parts of its surface from the corresponding parts of the surface of the respective said body.

2. An electron discharge device, comprising a cathode support, strip electrodes on opposite sides of said support and closely adjacent thereto, and separate electron emissive bodies on said support respectively adjacent each said electrode, the surface of each said body being substantially equal in area to the area of the respectively adjacent said electrode and substantially equidistant in all its parts from the corresponding parts of the surface of such electrode.

3. An electron discharge device, comprising a cathode support, strip electrodes on opposite sides of said support and closely adjacent thereto, and separate electron emissive bodies on said support respectively adjacent each said electrode, said electrodes being disposed with a substantially uniform distance between each surface element of said bodies and the corresponding opposed surface element of said electrodes, said distance being sufficiently short that the electron transit time from emissive body to electrode is small compared to the period of a wave having a frequency in excess of 500 megacycles.

4. A circuit for high radio frequencies, comprising a discharge device as set forth in claim 1, a resonant frame having two parallel conductive members connected together at their ends remote from said tube, means connecting the end of each of said members respectively to one of said electrodes, a tuning slider conductively connecting said members, input means connected to said slider, common means including an output impedance connecting said bodies to said slider and output leads connected to opposite terminals of said impedance.

5. A circuit for high radio frequencies, comprising a discharge device as set forth in claim 1, a resonant frame having two parallel conductive members connected together at their ends remote from said tube, means connecting the end of each of said members respectively to one of said electrodes, resonating means connecting said members, means to apply input potential to said electrodes, means including an impedance connecting said bodies to said frame at a point substantially in electrical symmetry with respect to said frame, and output leads connected to the terminals of said impedance.

6. A circuit for high radio frequencies, comprising a discharge device as set forth in claim 1, a resonant frame having two parallel conductive members connected together at their ends remote from said tube, means connecting the end of each of said members respectively to one of said electrodes, resonating means connecting said

members, means to apply input potential to said electrodes, means including an output impedance tunable to a desired transfer frequency connecting said bodies to said frame at a point substantially in electrical symmetry with respect to said frame, an oscillator operatively connected to produce in conjunction with the input frequency, the frequency to which said impedance is tuned, and output means operatively associated with said impedance.

7. An electron discharge device, comprising an electron emissive cathode, two narrow strip anodes disposed adjacent to but spaced from each other parallel to and substantially equidistant from said cathode on the same side of said cathode, a control electrode between each said anode and said cathode, and a focusing electrode extending from adjacent one of said anodes around said cathode but spaced therefrom and to a position adjacent the other said anode.

8. An electron discharge device, comprising a cathode support, a narrow strip electrode disposed adjacent thereto, and an electron emissive body on said support, said body being disposed facing said electrode and having a surface area substantially equal to that of said electrode, the distances between all surface elements on said body and the corresponding surface elements of said electrode being substantially equal.

9. An electron discharge device, comprising an electron-emissive cathode, two narrow strip anodes disposed adjacent to but spaced from each other parallel to and substantially equidistant from said cathode on the same side of said cathode, a plurality of electrodes disposed between said anodes and said cathode, and a focusing electrode extending from adjacent one of said anodes around said cathode but spaced therefrom and to a position adjacent the other said anode.

10. An electron discharge device, comprising an electron-emissive cathode, two narrow strip anodes disposed adjacent to but spaced from each other parallel to and substantially equidistant from said cathode on the same side of said cathode, control electrodes and accelerating electrodes successively disposed between said anodes and said cathode, and a focusing electrode extending from adjacent one of said anodes around said cathode but spaced therefrom and to a position adjacent the other said anode.

11. An electron discharge device, comprising an electron-emissive cathode, two narrow strip anodes disposed adjacent to but spaced from each other parallel to and substantially equidistant from said cathode on the same side of said cathode, an accelerating electrode, control electrodes, and a farther accelerating electrode successively disposed between said cathode and said anodes, and a focusing electrode extending from adjacent one of said anodes around said cathode but spaced therefrom and to a position adjacent the other said anode.

GEORGE E. PRAY.
SEBASTIAN RICCOBONO.
